(57) **CLAIM**

The ornamental design for a speaker for television receiver, as shown and described.

DESCRIPTION

FIG. 1 is a front perspective view of a speaker for television receiver showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof, shown in environmental use.

The broken line portions of FIG. 8 are included to show environmental use only and form no part of the claimed design.
